UNITED STATES PATENT OFFICE

HOWARD T. HALLOWELL AND FRANK BENNETT, OF JENKINTOWN, PENNSYLVANIA,
ASSIGNORS TO STANDARD PRESSED STEEL CO., OF JENKINTOWN, PENNSYLVANIA,
A CORPORATION OF PENNSYLVANIA

PORTABLE DESK

Application filed October 14, 1929. Serial No. 399,641.

One object of our invention is to make a portable desk of sheet metal, which can be used by shipping clerks and others and which can readily be moved to the place where the clerk is to check-off goods, or for any other purposes.

A further object of the invention is to so design the hinge that it will be substantial and will be hidden from view.

10 In the accompanying drawings:

Fig. 1 is a perspective view of our improved desk;

Fig. 2 is a sectional view on the line 2—2, Fig. 4, illustrating the improved hinge;

15 Fig. 3 is a side view of the hinge portion of the desk;

Fig. 4 is a sectional view on the line 4—4, Fig. 3; and

20 Fig. 5 is a detached perspective view of the hinge.

Referring to the drawings, 1 is the body of the desk having an inclined top 2, hinged to the body portion at the rear end. This top portion is provided with a flange 3 at the 25 front and at each side. At the rear of the top portion is a trough-shaped reinforcing member 4, which can be used as a receptacle for pencils and other writing material. The front flange 5 of this reinforcing member is 30 low and the rear flange is much higher than the front flange, so that when the top is raised to gain access to the interior of the desk, the articles in the receptacle will not roll off the rear of the top portion.

35 The body of the desk is supported on four legs 7, having braces 8, as shown in Fig. 1. The rear legs are provided with casters 9 and the front legs arranged to rest directly on the floor, so that when the desk is being used, 40 the front legs steady the desk and prevent it rolling, but when it is desired to move the desk, the front end of the desk is raised slightly, after which it can be readily moved on the casters to any position required.

45 The main feature of our invention is the hinge by which the top is pivotally mounted on the body portion.

Referring to Figs. 2, 3 and 4, 10 is one side 50 of the body portion and 11 is the deep flange of the top portion 2. This flange is prefer-

ably turned inwardly as at 12, to reinforce the top.

The hinge 13 is shown clearly in Fig. 2. One leaf 14 of the hinge is secured to the side of the body portion by bolts 15, while the other leaf 16 is secured to the flange 11 of the 55 top by bolts 17. The two leaves are bent towards each other as at 18 to form flattened ends 19, which are pivotally connected by a rivet 20, or any other suitable pivot pin. The flattened portions are held in contact with each other so as to hold the top portion against lateral movement.

When the top is raised, the leaf 16 turns on the pivot 20. The hinge is concealed not only by the deep flange 11 of the body portion 2, but also by the inturned end of the flange 12 when the top is raised, giving the desk a very neat appearance.

This type of hinge is very substantial and 70 cannot be readily broken by rough usage.

In Fig. 1 we have shown a drawer 21, arranged to slide under the body portion 10, but this may be omitted without departing from the essentials of the invention.

It is to be understood that there is a hinge 75 at each side of the desk.

We claim:

1. The combination in a desk, of a body portion; a flanged top portion of greater 80 width than the body portion; and hinges made of two sheet metal strips and bent so that the pivot portions of the hinge will be close together, while the two leaves of each hinge will be spaced apart, one leaf of each hinge being secured to the side of the body portion and the other leaf being secured to the flange of the top portion.

2. The combination in a desk, of a body portion; a flanged top portion of greater 90 width than the body portion and having a deep flange at each side, the lower portions of each flange being turned inwardly towards the side but not in contact therewith; and a hinge member located at each side of the desk 95 near the rear thereof and in the space between the side walls of the desk and the flanges of the top portion, the inturned portion of each flange extending under the hinge.

3. The combination in a metallic desk, of a 11

body portion made of sheet metal; metallic legs supporting the body portion of the desk; a top portion having deep flanges which are unturned at the lower edges; a trough-shaped 5 reinforcing member extending across the top of the desk, one edge of the trough-shaped member being higher than the other; and hinges located in the space between the side flanges of the top portion and the sides of 10 the body portion.

15 4. The combination in a desk, of a body portion; a top portion flanged at each side; a hinge located in the space between each flange and the body of the desk, the hinges being of sheet metal and bent to provide extended flat surfaces; and transverse pivot pins extending through the flat surfaces of 20 the hinges.

HOWARD T. HALLOWELL.
